UNITED STATES PATENT OFFICE

JESSE C. MARTIN, JR., OF LOS ANGELES, CALIFORNIA

SELF SUPPORTING WATER BOTTOM

Refiled for abandoned application Serial No. 301,124, filed August 21, 1928. This application filed August 17, 1932. Serial No. 629,244.

The invention relates to boilers and has as an object the provision of a boiler equipped with a water bottom that is self-supporting between the water legs of a boiler.

5 It is a further object of the invention to provide a self-supporting water bottom that may be readily installed.

It is a further object of the invention to improve in some respects upon the device disclosed in my Patent No. 1,663,806, dated 10 March 27, 1928.

Further objects of the invention will appear from the following description when read in connection with the accompanying 15 drawings showing physical embodiments of the invention, and wherein:—

Fig. 1 is a detail central vertical section of a portion of a firebox showing the invention installed;

20 Fig. 2 is a perspective view of one-half of one form of the invention;

Fig. 3 is a vertical transverse section through the firebox of a boiler showing the form of the invention of Figs. 1 and 2 installed therein;

25 Fig. 4 is a detail transverse section of a modification of the form of the invention shown in Figs. 1 to 3;

Figs. 5 and 6 are detail transverse sections 30 of a portion of a firebox showing further modifications of the invention, and

Fig. 7 is a detail central vertical longitudinal section of the form of the invention shown in Fig. 6, showing the air opening 35 in the bottom of the firebox but omitting the fire brick.

As shown in Figs. 1 to 3 inclusive, the invention is applied to the firebox of a boiler, a locomotive firebox having been chosen for 40 purposes of illustration, which boiler comprises a front water leg 10, a rear water leg 11, and side water legs 12, 13, the water legs downwardly terminating in a mud ring 14.

As shown the water bottom comprises a 45 carrier sheet 15 shown in this form of the invention as comprising the lower wall of each of the water bottom units illustrated, the carrier sheet 15 being turned downwardly at its edges as at 16, there being welded or otherwise secured to the mud ring. The

water bottom in this form of the device is shown as comprising two chambers, one opening into each of the side water legs of the boiler and the entire length of the water bottoms is less than the length of the firebox 55 so that it terminates short of each end thereof, as clearly shown in Fig. 1.

To complete the chambers of the water bottom, there are shown sheets of material 17 having their lower and end margins turned 60 downwardly at 18, 19, and 20, the edges of said margins being welded to the carrier sheet 15. The remaining margin of each sheet is turned upwardly as at 21 and the ends 22, 23 of the end margins 19, 20 are 65 also flared outwardly merging into the upturned margin 21, the lower edges of portions 22, 23 being welded to the carrier sheet 15 as indicated at 24, it being understood that the portion 22 is likewise secured to the 70 carrier sheet.

The flanges 16, 21, 22, 23, as completed fall into a surface which may when placed in the boiler form a portion of the inside side sheet thereof, the edges of flanges 21, 75 22, and 23 being welded to the edge of an opening in the side sheet into which the flanges seat. In the case of the application of the invention to existing boilers, said opening may be formed by cutting out the inside 80 side sheets by the use of an oxyacetylene torch.

To provide ample strength for supporting the water bottoms without the use of underlying slings, the carrier sheet 15 is desirably 85 made heavier than the remaining portions of the water bottom and heavier than the usual side sheets of the boiler. The carrier sheet must be sufficiently heavy to bear not only the weight of the water bottoms and 90 the water contained therein, but must also support the refractory linings to be described and, if necessary, the weight of workmen when making repairs upon the boiler, carrying such weights without support at its ends 95 since the water bottom as shown terminates short of the ends of the firebox. In making repairs upon boilers, it is often necessary to place jack screws between the bottom of the firebox and the crown sheet of the boiler and 100

the carrier sheet 15 must be sufficiently strong to avoid deformation even when making such repairs.

In Figs. 1 to 3 inclusive, the separate units of the water bottom shown are spaced apart at the center of the firebox and an air inlet opening 25 is provided through the carrier sheet, the remainder of the space between the units being lined with refractories, as firebrick 26, a frame 27 being desirably placed about the opening.

Cross plates 28, 29, Fig. 1, are supported upon the ends of carrier sheet 15 and housing plates 30, 31 are shown to complete the enclosure of the firebox at the ends of the water bottom. A flash wall 32 of refractory material and a filling 33 of the same material are shown at the rear end of the firebox and at the front thereof a lining 34, 35 of refractory material is shown to complete the protection of the housing.

If desired the carrier sheet 15 may be initially formed in two parts which may be edge-welded together as indicated at 36, Fig. 8, or the two parts thereof may be lapped and riveted or otherwise secured together as indicated at 37, Fig. 4. This modification may be utilized for the purpose of a more ready insertion of the structure into existing fireboxes.

Blow-off connections 38 are shown by way of flanged connections secured to the lower side of the carrier sheet 15 about openings therein. A liquid fuel burner is diagrammatically illustrated at 39.

In the modification shown in Fig. 5, the carrier sheet 15' forms the upper wall of the water bottoms and the lower wall thereof, shown at 40, may be secured to the carrier sheet 15' in the same manner as illustrated for the wall 17 of the form of the invention shown in Figs. 1 to 4 inclusive. In this form also a refractory lining 26' is shown superposed upon the sheet 15' to protect the portion thereof which is not protected by contact with water or steam.

In the modification shown in Figs. 6 and 7, the water bottom is made continuous across the firebox and is provided with a central blow-off connection 41. In this form of the invention the lower wall of the water bottom serves as a carrier sheet, the ends of the upper wall 43 being bent downwardly as at 44, Fig. 7, and the edges of the sheet 43 are also bent downwardly as at 45 to be secured to the lower wall 42 about the air inlet opening 46, which opening thus passes completely through the water bottom. A lining of refractory material 47 is shown over the center of the continuous water bottom to provide a locality of less heat to assist in the circulation of water in the water bottom, and to prevent warping.

The upper wall 43 in this form of the invention has its edges turned in flanges corre-

sponding to portions 21, 22, 23 of Figs. 1 and 2, a welded line 24' being indicated where the lower edges of flanges 22', 23' are secured to the ends 15' of lower wall 42.

In the form of Figs. 6 and 7, the invention is desirable for use in locomotives of smaller size than the other forms shown.

Minor changes may be made in the physical embodiment of the invention within the scope of the appended claims without departing from the spirit thereof.

I claim:

1. A self-supporting water bottom comprising, in combination, a relatively heavy carrier sheet forming one wall of a water enclosing space having an air opening adjacent its central portion, a second relatively light sheet spaced from the first named sheet forming a second wall of the water enclosing space, the end margins of said second sheet and portions thereof adjacent the longitudinal edges of said opening turned into contact with and joined to said carrier sheet to complete a water containing enclosure.

2. A multiple unit self-supporting water bottom comprising, in combination, a carrier sheet extending between the side water legs of a boiler and secured thereto adjacent one edge of an opening formed in each water leg, a pair of sheets completing each unit of the water bottom, the bodies of said last named sheets spaced from the carrier sheets and having their inner and end margins turned toward and secured to the carrier sheets and their outer margins secured to said water legs adjacent the opposite edges and ends of said openings, and means to conduct water from the barrel of the boiler to said units.

3. A self-supporting water bottom comprising, in combination, a relatively heavy carrier sheet having its side margins turned at an angle to the body thereof for attachment to the side water legs of a firebox at one side each of an opening in each water leg, a pair of sheets of relatively lighter material having side and end margins turned to contact with and secured to the surface of the carrier sheet with the body of said second sheets spaced from the carrier sheet to enclose water bottom units, the outer margins of each of said second sheets turned at an angle to the body thereof for attachment to said water legs at the remaining sides and ends of said openings whereby to provide a water bottom which is self-supporting between said side legs.

4. A self-supporting water bottom comprising, in combination, a relatively heavy carrier sheet forming the bottom wall of the water bottom and having its side margins turned downwardly for attachment to the mud ring of a boiler at the sides of a firebox, a relatively lighter plate spaced from said carrier sheet completing the enclosure of a

water containing chamber, having its end margins turned to contact with and secured to the surface of the carrier sheet and having a side margin turned into a flange for attachment to the inside side sheet of a firebox at a side and the ends of an opening therin adjacent the mud ring.

In testimony whereof I have hereunto set my hand this 13th day of August, 1932.
